METHOD AND MEANS OF CRACKING
PETROLEUM OILS

Harald E. Lonngren, New York, N. Y.

Application April 3, 1943, Serial No. 481,775

5 Claims.

(Cl. 196—63)

My invention relates to methods and means for cracking petroleum oil and has particular reference to the art of cracking in which heat, required for the conversion of hydrocarbons, is transmitted directly to the treated oils without the use of coiled pipes and pipe stills.

One of the serious disadvantages of ordinary cracking processes is that the treated oil must pass through relatively long pipes in order to obtain more efficient heat exchange. Petroleum oils, however, when heated under cracking conditions, precipitate coke and other hard residues and products of condensation, which rapidly clog the pipes and prevent efficient operation of the system.

One of the objects of my invention is to provide means and a method for conducting my cracking process in a relatively large chamber in which hard residues are not readily formed, and if present, cannot affect the efficiency of operation.

Another object of my invention is to provide an arrangement whereby the cracking heat is communicated to the oil directly by means of a suitable gaseous heat carrier, for which purpose the oil is introduced into the cracking chamber in a finely atomized or pulverized state and is thoroughly mixed with an inert gas or vapor, heated to a desired temperature. I have found that superheated steam forms a very convenient heat transferring medium. The material therefore receives its heat through direct contact with the heat carrier, without the use of intervening or separating metal walls as in ordinary pipe stills. The heat exchange takes place, therefore, rapidly and efficiently, due to the very large surface area of the minute particles of oil, each individual particle receiving its share of heat directly from immediately surrounding particles of the heat carrying fluid.

Another object of my invention is to provide means to produce turbulence in the cracking chamber for more efficient interchange of heat between the oil particles and the heat carrying fluid. I provide for this purpose atomizing and spraying nozzles for the chamber which direct the sprays eccentrically or obliquely to the axis of the chamber, thereby creating a whirling turbulent body of the atomized oil. I also provide means to direct the jets of the inert fluid in a general direction of the whirling mass, thereby causing the mixture to whirl energetically around, greatly expediting the cracking process. With my arrangement it is also possible, at all times, to maintain the process under control by regulating the relative amounts of oil and fluid, also the velocity of their movement.

My system has an important advantage in that the cracking vessel can be made of any suitable form and can be mounted either vertically or horizontally as the space permits, since the proc-

ess does not depend on gravity or other factors, limiting the design and position of the parts.

Another advantage of my process is that it can be carried with equal success in large vessels for large production or in relatively small containers when the production is limited.

Another object of my invention is to provide means to maintain the walls of the cracking vessel free from coke and other hard sediment. I provide for this purpose a jacket around the vessel with nozzles extending inward from the jacket at an angle to the axis of the vessel in a generally tangential or oblique direction. The nozzles are so arranged that the issuing jets of superheated steam or other fluid move along the walls, blowing off any sediments which may be settled or precipitated thereon.

Still another object of my invention is to provide means to remove any small solid particles from the cracked gases issuing from the vessel. I provide for this purpose a spray of oil or other suitable liquid in the pass of the exhaust gases, the liquid being delivered in the form of a plurality of fine sprays forming a curtain or screen, effectively entraining all the solid particles from the gases.

My invention in one of its practical embodiments is described more fully in the accompanying specification and drawing in which:

Fig. 1 is an elevational view partly in section of my cracking vessel, showing atomizers for the oil to be treated, also nozzles for the hot fluid, coke removing curtain-forming arrangement, and other details.

Fig. 2 is a sectional view taken on the line 2—2 of Fig. 1.

Fig. 3 is a sectional view taken on the line 3—3 of Fig. 1.

My cracking apparatus consists of an inner shell 1 and an outer shell 2, preferably of cylindrical shape with closed end portions 3 and 4. Petroleum oil or other liquid hydrocarbon to be cracked is introduced into the vessel through atomizing nozzles 5, 5.

The nozzles may be of any ordinary construction in which a liquid is finely dispersed by the action of compressed air or steam. The nozzles are fitted in the inner and outer shell and extend in a generally tangential or oblique direction with reference to the inner portions of the vessel. As a result, the atomizers form a fine mist in the vessel, whirling in a plane perpendicular to the axis of the vessel.

A suitable inert heat carrier such as superheated steam or other suitable elastic fluid, is introduced into the vessel through a central pipe 6, supported axially of the vessel and closed at the inner end 7, the outer end being connected to a suitable supply pipe 8. The pipe 6 is provided with radial projections 9 having apertures 10 through which steam emerges in a plurality of fine

jets. The apertures 10 are directed in a substantially tangential direction to the pipe 6, so that the jets form a whirling body in the vessel, rotating in the same direction as the mist, formed by the nozzles 5. Steam thus is brought into an intimate contact with the minute particles of the oil, surrendering its heat for recombining the molecules of the oil into a cracked product. Because of the minute dimensions of the individual particles and their rapid turbulent motion, the cracking process takes place very rapidly, the resultant cracked vapors and gases escaping through an exhaust pipe 11 at the end of the vessel.

A certain amount of steam is diverted through openings 12 into a jacket space 13 between the shells 2 and 3 where the hot steam helps to maintain the required temperature in the cracking chamber 14. Steam escapes from the chamber through apertures 15 in the form of fine jets. These apertures are provided in depressions 16, the apertured walls extending in substantially radial direction so that the jets follow approximately the inner surface of the shell 3 as shown in Fig. 2. The innumerable steam jets form a blanket at the surface of the inner shell, preventing formation of coke and other hard deposits, and removing such deposits as may form from time to time. By this arrangement one of the greatest difficulties in the operation of cracking equipment is eliminated, there being no interruption with my system on account of clogged pipes.

The minute particles of coke and solid products of condensation of cracked hydrocarbons, being unable to settle on the walls of the vessel, will remain suspended in the gases. To remove them, I provide an arrangement shown at the right in Fig. 1 and consisting of a spraying chamber 17 at the upper portion of the vessel in communication with a pipe 18 through which a suitable liquid is delivered, such as oil, water, etc. The inner wall 19 of the spraying chamber is provided with a large number of minute perforations 20 through which the liquid emerges in the form of fine jets 21, forming a curtain at the end of the vessel in front of exhaust pipe 11. The perforations or holes are staggered in order more fully to cover the path of the gases so that all impurities and coke particles are washed down with the jets into a collector 22 at the lower side of the vessel. The contaminated liquid 23 is removed through the lower end of the collector by a suitable pipe 24 into a filter (not shown) or other purifying agency for removing the solid particles and rendering the liquid suitable for further use.

The main vessel is shown of a cylindrical shape, although, of course, it can be made of any other suitable shape, preferably as a body of revolution to facilitate the whirling effect produced by the various jets. It should be also noted that the body may be placed in any convenient position, not necessarily horizontal, since no part of the cracking process proper depends on gravity, and the jets will be equally effective for any position of the vessel.

Because of rapid and thorough heat exchange in my device, no portion of my apparatus will require any excessive heating, and the cracking reaction will flow very satisfactorily with steam superheated to about 800°-1400° F. and at pressures from about 5 to about 50 psi.

My system has a particular advantage that it allows the use of high cracking temperature since there is no coke formation to interfere with the

process. Moreover, the operative temperature and pressure can be easily and quickly changed to suit the particular cracking characteristics of the stock used.

5. It is understood that my method and means for cracking petroleum oils may be further modified without departing from the spirit of the invention, as set forth in the appended claims.

I claim as my invention:

10. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

15. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

20. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

25. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

30. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

35. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

40. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

45. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

50. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

55. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

60. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

65. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

70. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

75. An apparatus for cracking petroleum oil comprising a cylindrical vessel; a plurality of nozzles supported at spaced intervals along the cylindrical wall of the vessel and extending inwardly in tangential direction; the nozzles being adapted to admit oil into the vessel; a tube supported axially in the cylinder throughout its length; having a plurality of openings extending into the vessel, the tube being adapted to receive an elastic fluid; and means to exhaust the vaporous mixture of the oil with the elastic fluid at the end of the vessel.

5. A method of cracking petroleum oils, consisting in forming a cylindrical rotating body in a confined space, the body comprising a mixture of a minutely atomized oil with steam; causing the mixture to move in an axial direction toward one end of the confined space; and exhausting the mixture at the end of the confined space through a screen of a flowing liquid.

HARALD E. LONNGREN.
